UNITED STATES PATENT OFFICE.

JOHN L. TAYLOR, OF CHICAGO, ILLINOIS.

DERRICK.

1,032,251.

Specification of Letters Patent.

Patented July 9, 1912.

Application filed July 19, 1911. Serial No. 639,364.

To all whom it may concern:

Be it known that I, JOHN L. TAYLOR, a citizen of the United States, residing at Chicago, in the county of Cook and State 5 of Illinois; have invented certain new and useful Improvements in Derricks; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to new and useful improvements in derricks and the object in view is to produce a simple apparatus of this nature especially adapted for use for unloading gondola cars and for hoisting 20 purposes generally.

The invention comprises various details of construction and combinations and arrangements of parts which will be herein-after fully described and then specifically 25 defined in the appended claims.

I illustrate my invention in the accompanying drawings, in which:—

Figure 1 is a perspective view of my device shown as applied to a platform and 30 adapted to be held over the side wall of a gondola car. Fig. 2 is a sectional view through the wall of a car and showing the manner of adjustably holding the device in place. Fig. 3 is a sectional view through the 35 lower portion of the standard of the derrick, showing means for holding a cable passing therethrough, and Fig. 4 is a bottom plan view showing a slightly modified form of the device when used independent of the 40 platform. Fig. 5 is an elevation in section of a modification.

Reference now being had to the details of the drawings by letter, A designates a platform having angle irons B fastened to the 45 under surface thereof, and C designate brackets fastened to said angle irons and adapted to be positioned relative to the wall D of a car in the manner shown in Fig. 2 of the drawings. Angle irons or beams E 50 are mounted upon the platform, preferably in the manner shown, and are held in place by means of bolts E' passing through the two sets of angle irons and the platform and are held in place by means of the 55 winged nuts F. The angle bars H also serve to hold the beams E in place by means

of the screws H' and winged nuts H² thereon. A plate L is bolted or otherwise secured to the two beams E and upon which is supported the standard N of the derrick, 60 said standard being provided with suitable braces N', the lower ends of which are fastened to the beams E and their upper ends to the standard. A flange O projects from the standard at any suitable location and is 65 adapted to support the anti-friction rollers Q which are journaled upon the pins Q' carried by the arms J. The inner ends of the pins Q' are mounted in a semi-cylindrical bearing member Q², the inner concaved surface of which bears against the standard as the derrick turns. A yoke S, of which the arms J are an integral part, has a reel S' journaled in arms S² thereon and is provided with a plate S³ which is apertured at 70 S⁴ for the reception of the upper end of the standard, a suitable flange S⁵ projecting from the upper portion of the standard and upon which the plate rests. The swinging beam S⁶ of the derrick is provided with 75 pulleys S⁷ and a cable S⁸ passes about the pulleys and is adapted to wind upon the drum. An operating handle S⁹ is fastened to the spindle of the drum and a ratchet wheel S¹⁰ is fixed to the spindle of the 80 drum and is engaged by a pawl P adapted to hold the reel from rotating in one direction.

Referring to Fig. 2 of the drawings, it will be seen that an adjustable bracket member T is provided which is held in one or another of the apertures T' by means of the bolts T² and the two brackets C and T are adapted to frictionally engage the side of a car, while a chain G is fastened to the under surface of the standard and is adapted to be secured to a car or any other object not shown.

In Figs. 3 and 4 of the drawings I have shown a slight modification of the apparatus in which the hoisting cable I may be passed through an opening I' formed in the two angle beams I², shown in dotted lines in Fig. 4, and which angle beams are adapted to be supported upon any structure independent of the platform when it is desired to hoist objects by my improved derrick and in which modified form a plate M is provided which is fastened to the angle irons in any suitable manner and has a flange M' fitting over the adjacent edges of the two meeting ends of the angle irons or beams, 100 105 110

and hangers W are pivotally mounted upon the pins W' fastened to the plates W^2 which are held by screws W^3 to the beams or angle irons. Each of said hangers carries a pulley X which is adapted to frictionally engage the cable and held in such position by means of the coiled spring X' secured to the lower ends of the hangers.

It is my purpose in the modified form to utilize a team or other suitable power which may be applied to the cable and, by the provision of the springs, the pulleys will hold the cable from slipping.

In Fig. 5 of the drawings, the cable is adapted to pass over the drum and centrally through the aperture and to be engaged by the friction rollers and thus held securely. When the load is elevated, the horse or other power attached to the cable may be released and the load may be held by the ratchet and dogs until the load is swung to the desired place, after which by releasing the pawls the load may be lowered by operating the crank.

What I claim to be new is:—

25. 1. A derrick comprising a standard and means for supporting the same, flanges projecting from the circumference of the standard and spaced apart, a swinging beam with arms thereon, a yoke to which said beam is fastened, anti-friction rollers carried by said arms and mounted upon one of said flanges, an apertured plate forming a part of said yoke and engaging loosely over the upper portion of the standard and resting upon one of said flanges, a drum journaled in said yoke, pulleys upon the beam, and a cable passing about said pulleys and drum.
30. 2. A derrick comprising a standard and means for supporting the same, flanges projecting from the circumference of the stand-

ard and spaced apart, a swinging beam with arms thereon, a yoke to which said beam is fastened, anti-friction rollers carried by said arms and mounted upon one of said flanges, a semi-cylindrical bearing member between 45 said arms and bearing against the standard, an apertured plate upon the yoke receiving the upper end of the standard and resting upon one of said flanges, a drum journaled upon the yoke, and pulleys upon the beam, 50 and a cable adapted to pass about the pulleys and drum.

3. A derrick comprising a hollow standard, a swinging beam mounted thereon, a yoke carried by the beam, a drum upon said 55 yoke, a cable passing about the drum and through the standard, hangers fastened at the bottom of the standard, friction pulleys mounted upon the hangers, a spring connecting the hangers and adapted to hold the 60 friction pulleys against the cable.

4. A derrick comprising angled beams which are apertured, a hollow standard rising from said beams, a yoke supported by the standard, a drum upon the yoke, a cable 65 passing about the drum and through apertures beneath the standard in said beams, hangers pivoted to the under surface of the beams on the opposite sides of said apertures, friction pulleys carried by the hangers and between which pulleys said cable passes and a spring holding the pulleys 70 against the cable.

In testimony whereof I hereunto affix my signature in the presence of two witnesses. 75

JOHN L. TAYLOR.
